CLAIM

The ornamental design for a cover for a battery compartment of a remote control, as shown and described.

DESCRIPTION

FIG. 1 is a top, left and front perspective view of the cover for a battery compartment of a remote control showing my new design in closed position;

FIG. 2 is a top, left and front perspective view thereof in open position;

FIG. 3 is a top plan view thereof;

FIG. 4 is a front view thereof;

FIG. 5 is a right side view thereof, the left side being a mirror image;

FIG. 6 is a rear view thereof; and,

FIG. 7 is en exploded view thereof.

The bottom plan view of the cover for a battery compartment of a remote control is flat and devoid of surface ornamentation.

The broken lines in FIGS. 1, 2, 4–7 showing the remote control, the battery compartment and a means for securing the cover for a battery compartment to the remote control are for illustrative purpose only and form no part of the claimed design.
